CLAIM

The ornamental design for a portion of a dispenser housing, as shown and described.

DESCRIPTION

FIG. 1 is a front elevational view a portion of a dispenser housing showing my new design;

FIG. 2 is a left side elevational view thereof, the right side elevational being a mirror image thereof;

FIG. 3 is a top plan view thereof;

FIG. 4 is a bottom plan view thereof; and,

FIG. 5 is a rear elevational view thereof.

The broken line showings of the slot in the bottom front; the raised triangular ledge in the bottom, and the quarter-circle-shaped recesses in the sides are for illustrative purposes only and do not form part of the claimed design.
